UNITED STATES PATENT OFFICE

2,546,229

TELEPHONE MOUTHPIECE STERILIZING DEVICE

Arthur P. McCloskey, Oak Park, and Ervin W. Hopkins, Hinsdale, Ill.; said Hopkins assignor to said McCloskey

Application June 1, 1948, Serial No. 30,494

2 Claims. (Cl. 21—61)

1

This invention relates to a telephone sterilizing device. More particularly, the invention relates to simple means for supporting a germicidal composition effective in a vapor state for destroying germs on telephone mouthpieces.

A variety of suggestions have been made for the treatment of telephone mouthpieces to destroy pathogenic bacteria thereon and preventing the spread of diseases through contact with germs on telephone mouthpieces. Substantially none of the suggested structures have been adopted and several reasons are obvious which prevent their adoption. Some of the materials employed are dangerous and the proposed use of them involves too great a hazard. The germicidal compositions are invariably liquids and these require containers which are difficult to support safely and which may be overturned, etc. Some of the suggested materials vaporize at a high rate for a short period of time and are then exhausted; further, the vaporized material forms an undesirable component of the room atmosphere. Certain of the suggested supporting devices are equipped with means for engagement by the mouthpiece in order to open the container for evaporation only when the mouthpiece is in position on the support. The structure is not satisfactory because the mouthpiece may shift longitudinally of the support and thus fail to open the container. Substantially all of the structures suggested are expensive and complicated. For the successful treatment of the millions of telephones employed, the need for many decades has been for an extremely simple structure supporting a germicidal composition in an effective position with respect to the mouthpiece while at the same time providing a unit containing the germicidal composition which may be replaced readily from time to time.

An object of the present invention is to provide a structure filling the need above referred to and having the desired qualities set out. Yet another object is to provide a simple structure and means for disinfecting telephone mouthpieces which will avoid the undesirable qualities in the structures above referred to while providing an extremely simple and inexpensive arrangement in which a simple disc structure encloses the germicidal composition in a protective manner. A still further object is to provide a protective disc of a porous or fibrous composition containing therein a solid disinfectant in a protected manner, the disc being supported in effective germicidal position with respect to the mouthpiece and being replaceable as needed. Other specific objects and advantages will appear as the specification proceeds.

The invention is illustrated in a single embodiment, by the accompanying drawing, in which—

Fig. 1 is a perspective view of a telephone receiver or stand equipped with a speaker arm and

2

mouthpiece, the structure being provided with sterilizing or disinfecting means embodying our invention; Fig. 2, a broken vertical sectional view on an enlarged scale; Fig. 3, a detail transverse section view, the section being taken as indicated at line 3 of Fig. 3; Fig. 4, a perspective and partly sectional view of a disc structure embodying our invention; and Fig. 5, a broken view in vertical section showing a modified structure embodying our invention.

In the illustration given, A designates the usual telephone stand upon which is supported a speaker and receiver arm B. The arm B is provided with a circular speaker ring or mouthpiece B¹.

In the illustration given in Figs. 1 to 4 inclusive, we provide a base plate 10 having an inwardly extending bottom flange 11 upon which the stand A is adapted to rest. The member 10 is provided with a vertical portion having inwardly extending arms 12 forming a channel 13. The arms 12 are turned outwardly at their ends 14 and are welded to a U-shaped channel member 15. The U-shaped channel member 15 receives the outer flange 16 of the telephone stand A, as shown more clearly in Fig. 2, and the outer lip 17 of the U-shaped member 15 lies against the inner wall of the casing member 16. By this means, the frame wall 15 is locked tightly about the flange 16 and the member 10 is anchored firmly in the position illustrated in Fig. 2.

A slideable support arm 18 is provided with a screw 19 which extends through the arm 18 and through a slot 20 in the vertical flange of member 10. The screw 19 is provided on its inner end with a nut 21 which is received within the channel 13. The arm 18 is thus adjustably mounted upon the support 10.

As shown more clearly in Fig. 2, the upper end of the support 18 is inclined forwardly at an angle of about 25° to provide a supporting flange 22 which is welded or otherwise secured to a shallow pan 23.

The shallow pan 23 is open at its top and is supported with the bottom wall of the pan adjacent to and in substantially parallel alignment with the bottom wall 24 of the mouthpiece B¹, as shown best in Fig. 2. Within the shallow pan is supported a germicidal disc 25.

The germicidal disc 25 may be formed of any suitable material. We prefer to form the disc of porous material and to place the germicidal substance within the central portion of the disc so that the disc serves as a protective body about the germicidal substance. The disc may be formed of cotton pads pressed together, plaster of Paris, molded paper pulp, etc.

Formaldehyde and paraformaldehyde have been heretofore suggested for use for the fumigation of infected premises. To render the solid

polymer, paraformaldehyde, effective, other chemicals or heat have been employed to produce evolution of the vapors. Such vaporization has been employed for brief periods and in the absence of human beings. The literature indicates that the normal vaporization from the solid polymer resulted in too low concentrations in the air to have germicidal effect.

We have discovered that the solid polymer, paraformaldehyde, is unusually effective as a means for disinfecting telephone mouthpieces and particularly when employed apart from any heat or reacting material. By incorporating the solid within a porous disc, and preferably by means of a non-reactive adhesive, we find that the telephone mouthpiece can be effectively sterilized within a brief period and maintained sterile over long periods of time, the disc which supports the paraformaldehyde being replaced only after a substantial period of days. The solid polymer supported within the interior of the disc is found to have effective germicidal action with respect to the telephone mouthpiece after periods of about a month. The slow vaporization, however, of the material does not render a room unpleasant and, in fact, does not require a masking vapor odor.

In the illustration given in Fig. 5, the telephone stand body is received within a simple tray 26. The tray supports a channel member 27 which is slotted to receive a screw 28 and a member 29a similar to the support 18 already described is employed for supporting the pan 23. With this structure, it will be noted that the supporting mechanism is not in any way connected to the telephone apparatus, the stand A merely resting freely within the tray.

The disc 25, in the specific illustration given, is formed in two parts. There is an upper cotton pad 29 and a lower similar cotton pad 30. Paraformaldehyde powder was mixed with a vegetable adhesive, sodium alginate, and applied to the upper surface of the lower pad 30 in concentric circles approaching the center of the pad, as illustrated in Fig. 4. Thus the paraformaldehyde was fairly evenly distributed over the top of the lower disc. The two pads were then pressed together and the adhesive served to bind them into a united disc. The viscosity of the adhesive was such as to prevent penetration of the lower disc to any substantial degree and the fibrous pads thus provided ample protection to prevent the user from coming into contact with the solid polymer.

In another example, the dry paraformaldehyde powder was mixed with gum arabic and deposited in the manner above described to provide a good product.

In another example, the paraformaldehyde powder was mixed with gum tragacanth and the viscous material applied fairly evenly over the lower pad but spaced inwardly, as in the previous examples, from the extreme edge of the pad. The two pads were then pressed together and united.

In another example, the above mixtures were used with molded paper pulp to form the porous pads. Similarly, we have united separate discs of plaster of Paris by means of the adhesives employed. We find that any vegetable adhesive may be used. It is important that an adhesive be employed which does not contain nitrogen.

We prefer to support the pan 23 at an angle of about 25° with the horizontal plane, this being the plane of the mouthpiece ring 24 and we prefer to adjust the pan so that it is at a distance of

about 8 mm. from the mouthpiece 24. At lesser distances, even more effective results are obtained.

Germicidal tests were carried out by applying diluted broth cultures of certain pathogenic bacteria to sterilized telephone mouthpieces with cotton swabs. After drying for a fixed interval, one-half of the mouthpiece was swabbed, and plate cultures made from the swab. The mouthpiece was then placed on the support above a disc 25 containing paraformaldehyde, and after a definite period of time the second half of the mouthpiece was swabbed and the swab cultured. In many of the tests, as many mouthpieces were reserved as controls as were exposed to the germicide, in order to determine any lethal effect of holding the dried bacteria during the time necessary to carry out the test. The time of exposure to the germicide extended from one hour down to periods of five minutes or less. Most of the tests were made in periods of about five minutes and it was at this time that the effect of the paraformaldehyde contained in the disc became very apparent in the percentage kill of bacteria on the telephone mouthpiece. In testing for *Staphylococcus aureus* at 8 mm. distance, five minutes exposures, it was found that when the disc contained paraformaldehyde in a quantity of 0.50 gram and more, that the number of bacteria killed increased, the best results being obtained when the content of paraformaldehyde in the disc was from 1.0 to 2.0 grams. From about 1.5 to 2.0 grams, substantially all of the organisms were destroyed within the five minute exposure. While the percentage kill was from 95 to 100% in the period mentioned, obviously the destruction would be far greater for longer periods. Since in normal use the mouthpiece would be subjected over extremely long periods to the action of the germicidal vapor, a much lower content of paraformaldehyde could be employed than was used in the above tests.

Tests of the same kind were performed with other pathogenic bacteria. In general, most types of bacteria of concern in human disease are less resistant to drying than is *Staphylococcus aureus*, and as some of the results show, some of the organisms may be dying off during the period of the experiment without any other treatment than drying. In a test with the organism *Klebsiella pneumoniae*, the organisms were totally destroyed in the five minute period using 2.0 grams of paraformaldehyde. A similar test gave like results in the treatment of *Streptococcus pyogenes*.

The various tests demonstrated that paraformaldehyde when incorporated in a porous supporting material, exerts strong germicidal action in periods of five minutes and less at distances up to 8 mm. The tests further demonstrated that the solid polymer in the discs was effective for bringing about the above described results even after periods of from two to four weeks. The solid polymer was incorporated within glass wool and sponges, plaster of Paris, and similar materials by forming a solution of the paraformaldehyde and allowing it to penetrate the porous material while a liquid, the material solidifying then within the porous carrier. The paraformaldehyde on the outer surfaces was then removed.

While in the foregoing description, we have set forth structures in considerable detail for the purpose of illustrating one embodiment of the invention, it will be understood that such details may be varied widely by those skilled in

the art without departing from the spirit of our invention.

We claim:

1. A sterilizing pad adapted for use in the sterilizing of a telephone mouthpiece, comprising a pair of fibrous discs having interposed between them a thin layer of a high-viscosity vegetable adhesive having powdered paraformaldehyde carried therein in a state of suspension, the vegetable adhesive being operative to hold the paraformaldehyde in the space between the disks and operative also to secure the pads together to form a porous body through which vapors from the paraformaldehyde may pass.

2. A sterilizing pad adapted for use in the sterilizing of a telephone mouthpiece, comprising a pair of cotton pads having interposed between them a thin layer of sodium alginate solution having powdered paraformaldehyde carried therein in a state of suspension, the sodium alginate being operative to hold the paraformaldehyde in the space between the pads and operative also to secure the pads together to form a porous body through which vapors from the paraformaldehyde may pass.
